JOHN GAMBLE, OF PHILADELPHIA, PENNSYLVANIA, ASSIGNOR TO GEORGE A. REACH, OF PHILADELPHIA, PENNSYLVANIA.

BOXING-GLOVE.

SPECIFICATION forming part of Letters Patent No. 705,915, dated July 29, 1902.

Application filed December 18, 1901. Serial No. 86,388. (No model.)

To all whom it may concern:

Be it known that I, JOHN GAMBLE, a citizen of the United States, residing in Philadelphia, in the county of Philadelphia and State of Pennsylvania, have invented new and useful improvements in Boxing-Gloves, of which the following is a specification.

My invention relates to boxing-gloves; and the object of my improvement is to make a well-ventilated boxing-glove that can be made to snugly fit any one not having a hand of abnormal size or shape. Ordinarily boxing-gloves are made with a short V-shaped vent or opening at the top of the inside wrist portion. This vent is closed usually by lacing it up, so as to make the glove fit tightly around the wrist. This construction is satisfactory only when the glove fits the hand snugly; but when the glove is too small it is uncomfortable and hard to get into, and if it is a little too large the padding soon begins to shift and get out of place. To overcome these difficulties and to make a glove that will fit snugly upon any hand of normal size and shape, I make the inner or palm portion of the glove with a vent that extends from the wrist almost to the ends of the fingers and provide it with suitable lacing holes and cord. When the glove is made with this extended vent, it can be laced to fit snugly about any size of hand, and the long opening allows the free ingress of air for the purpose of ventilation. Lacing the glove to a snug fit has the effect of binding and holding together all the bones of the hand, so that the force of any blow is distributed over the whole hand and no single one of the bones is likely to be injured. To relieve the muscular strain incident to holding the hand tightly closed, I secure across the palm portion an adjustable palm-grip that is fastened at the ends thereof to the sides or edges of the glove. The middle portion of the grip is left entirely free, so that it can be moved back or forward, as the wearer has a long or short hand or as he may think is the most advantagous for him. To give a longer range of adjustment to the grip, I secure it upon and around an elastic strap or cord the ends of which are fastened to the sides or edges of the glove.

In the accompanying drawings, Figure 1 is

a view of the inside portion of a boxing-glove having my improvements therein. Fig. 2 is a side or edge view of the glove. Fig. 3 is a partial view of the inside of a boxing-glove, 55 showing a modified form of the palm-grip.

A represents the outer or padded portion of the glove, made in the ordinary manner and having the usual thumb-stall.

B is the palm or inner portion of the glove, 60 made with a vent extending from the wrist portion down through the palm and almost to the ends of the fingers. This vent is provided with holes and a suitable lacing-cord.

C is an adjustable palm-grip for grasping 65 in the hand to relieve the muscular strain. This grip is not connected to the palm of the glove in any way, but is held in position, preferably, by the elastic cord or webbing D, that passes through the central or middle portion of the grip and is secured at each end thereof to the sides or edges of the glove in the manner shown in Figs. 1 and 2. The grip may be fastened securely to the elastic or left to slide loosely over it, so as to be adjustable sidewise, if desired.

The palm-grip shown in Fig. 3 is secured directly to the edges of the glove without any intervening elastic portion. When made in this way, it is desirable to make the grip 80 slightly longer than the width of the glove and have the ends thereof somewhat tapering, so as to make it quite narrow or thin where it is fastened to the glove. This construction will give quite a wide range of adjustment without the use of the elastic webbing or cord shown in Figs. 1 and 2.

Having thus described my invention, what I claim as new, and desire to secure by Letters Patent, is—

1. A boxing-glove having in the palm thereof, a longitudinal vent or opening, adapted to be drawn together by any suitable means, and an adjustable palm-grip extending loosely across the palm of the glove and having its 95 ends secured to said glove.

2. As an article of manufacture, a boxing-glove having its inner or palm portion provided with a longitudinal vent or opening extending to a point approximately midway between the base of the fingers and the tips thereof, the sides of said opening being pro-

vided with closing means, whereby the glove may be adjusted to hands of different sizes, so as to closely incase both the body of the hand and the fingers thereof.

5 3. As an article of manufacture, a boxing-glove having its inner or palm portion provided with a longitudinal opening or vent extending from the top of the glove to a point approximately midway between the base of

10 the fingers and the tips thereof, said opening affording ventilation for the palm and fingers, and suitable lacing means for drawing the edges of the vent or opening together, so as to adapt the glove to be drawn snugly

15 around the body and fingers of the hand whether it be broad or narrow.

4. A boxing-glove having a palm-grip secured at its respective ends to the glove, said palm-grip lying across the palm and being

20 free to accommodate itself to the grip of different sizes or lengths of hands.

5. A boxing-glove having therein an adjustable palm-grip that extends loosely across

the inside of the glove and is fastened thereto only at the ends of the grip, substantially 25 as shown.

6. A boxing-glove having therein an adjustable palm-grip that extends loosely across the inside of the glove, and is secured thereto through an intermediate elastic portion at 30 the two ends of the grip, substantially as shown.

7. A boxing-glove having an adjustable palm-grip that extends loosely across the inner portion of the glove, and is secured thereto by an elastic cord or connection that passes through the grip and is attached at the ends thereof to the side of the glove, substantially 35 as shown.

In testimony whereof I affix my signature 40 in presence of two witnesses.

JOHN GAMBLE.
